UNITED STATES PATENT OFFICE.

MORRIS M. PEYSER, OF BOSTON, MASSACHUSETTS.

DESIGN FOR A SHAWL-BORDER.

Specification forming part of Design No. 2,492, dated October 9, 1866.

To all whom it may concern:

Be it known that I, MORRIS M. PEYSER, of Boston, in the county of Suffolk and State of Massachusetts, have invented or produced a new ornamental Design for a Knit-Shawl Border; and I do hereby declare the same to be fully exhibited in the accompanying photographic representation of a portion of a shawl made with such border.

It is what in commerce I term "No. 1400, Pomona," it being composed of a series of grape-leaves arranged at regular distances apart and having between each two of them a figure or representation of a bunch of

grapes, the same being, as shown in the photographic drawing, as wrought within a parti-colored ground. The design further includes two edgings for such, each being as shown in the figure, in which A is the ground, B B' the edgings, C C C the grape-leaves, and D D D the bunches of grapes.

I claim—

The said design as my invention or production.

M. M. PEYSER.
